UNITED STATES PATENT OFFICE.

ANNA M. H. CULP, OF DRAVOSBURG, PENNSYLVANIA.

CURTAIN-POLE.

SPECIFICATION forming part of Letters Patent No. 691,605, dated January 21, 1902.

Application filed October 31, 1901. Serial No. 80,692. (No model.)

To all whom it may concern:

Be it known that I, ANNA M. H. CULP, a citizen of the United States of America, residing at Dravosburg, in the county of Allegheny 5 and State of Pennsylvania, have invented certain new and useful Improvements in Curtain-Poles, of which the following is a specification, reference being had therein to the accompanying drawings.

10 This invention relates to certain new and useful improvements in curtain-poles; and the object of the invention is to provide a neat, simple, and durable pole with novel means for suspending a curtain therefrom in 15 such a manner that the point at which the curtain is suspended will be hidden from view when the curtain is in position.

Briefly described, my invention comprises a hollow pole, which may be made of wood or 20 metal, preferably the latter, and is slotted throughout its length along the underneath side. A curtain-supporting rod is inserted in this hollow pole and has enlarged cylindrical bushings on its ends, which fit the bore of the 25 pole, and thus hold the rod centrally of the pole. These bushings carry extensions to receive the curtain-knobs, all of which construction will be hereinafter more fully described, and specifically pointed out in the 30 claims.

In describing the invention in detail reference is had to the accompanying drawings, forming a part of this specification, and wherein like numerals of reference indicate corresponding parts throughout the several views, 35 in which—

Figure 1 is a front elevation of my improved curtain-pole, showing a curtain suspended therefrom. Fig. 2 is a longitudinal sectional 40 view of a part of the curtain-pole. Fig. 3 is a transverse vertical sectional view.

In the accompanying drawings the numeral 1 indicates the pole, which is preferably cylindrical and is hollow, being made either of 45 wood or metal, though preferably the latter. This pole 1 is provided throughout its length along the underneath side with a slot 2 for the reception of the curtain 3. The curtain is supported by means of a rod 4, which has 50 near each end cylindrical bushings or bosses 5, made to fit neatly in the bore of the curtain-pole 1, and thus hold the rod 4 centrally of the said pole. The curtain is wrapped around the rod 4 between the bosses or bushings 55 and may be sewed, as at 6, or may be merely

hung over the rod. The extensions 7 of the rod project beyond the ends of the curtain-pole 1 and are adapted to receive the ornamental knobs 8, which are cored to receive the said extensions 7. Placed on the ends of 60 the pole are threaded sleeves 9, the pole being threaded exteriorly at its ends to receive these sleeves. These sleeves are employed merely to prevent the enlarging of the pole 1, as when the rod 4 is inserted into the pole with 65 the curtain in the slot 2 and these sleeves 9 are threaded on to the pole the latter will be bound firmly upon the cylindrical bosses or bushings 5, and the rod thus held against longitudinal movement in the pole. 70

In the practice of the invention it will be noted that various changes may be made in the details of construction without departing from the general spirit of my invention.

Having fully described my invention, what 75 I claim as new, and desire to secure by Letters Patent, is—

1. In combination with a hollow cylindrical curtain-pole slotted throughout its length along the underneath side, of a curtain-supporting rod having integral cylindrical bushings or bosses formed thereon to fit the bore of the pole, integral extensions carried by said bushings or bosses to receive the knobs, and sleeves threaded on the pole to bind the latter 85 on the bushings, substantially as described.

2. In combination with a hollow curtain-pole slotted throughout its length along the underneath side, a curtain-supporting rod having integral bushings or bosses adapted to 90 fit the interior of the curtain-pole and having integral extensions to receive the curtain-knobs, and binding-sleeves mounted on the ends of the pole, substantially as described.

3. In combination with a hollow pole slotted from end to end along its underneath face and exteriorly threaded at its ends, a curtain-supporting rod having bushings or bosses to fit the interior of the pole, extensions carried by the rod to receive curtain-knobs, and 100 sleeves threaded upon the pole to bind the latter on the bushings or bosses, substantially as described.

In testimony whereof I affix my signature in the presence of two witnesses.

ANNA M. H. CULP.
